[57] **CLAIM**

The ornamental design for a power module for fiber-optic interface system, as shown and described.

DESCRIPTION

FIG. 1 is a perspective view of a power module for fiber-optic interface system;

FIG. 2 is a top plan view thereof;

FIG. 3 is a bottom view thereof;

FIG. 4 is a right side view thereof, the left side being identical thereto;

FIG. 5 is a front view thereof;

FIG. 6 is a rear view thereof; and,

FIG. 7 is a right side view, the left side being identical thereto, of the power module fiber-optic interface system shown in FIG. 1 with the top, bottom, front and rear views remaining the same as shown in FIGS. 2, 3, 5 and 6, respectively.

The broken line showing of is for illustrative purposes only and forms no part of the claimed design.
